UNITED STATES PATENT OFFICE

LOUIS T. MEDHOLDT, OF CINCINNATI, OHIO, ASSIGNOR TO THE J. A. FAY & EGAN COMPANY, OF CINCINNATI, OHIO, A CORPORATION OF WEST VIRGINIA

KNIFE GRINDER SUPPORT FOR WOODWORKING MACHINES

Application filed May 6, 1931. Serial No. 535,453.

This invention relates to woodworking machines of the type employing cutting knives as, for example, planers, surfacers and the like and more particularly to the means for supporting the sharpening mechanism for such knives.

Heretofore in machines of this class it has been the common practice to provide sharpening means for the cutting blades consisting of a blade setter, grinder and so-called jointing stone. These three units have been removably mounted upon a single rail carried by the machine but the manner in which they have been supported by the rail has several objections, to-wit: Being supported by one rail, the grinder as well as the jointing stone and setter have been overhung or supported on one side only. As the jointing stone and setter are not heavy units, one rail is usually sufficient but the grinder, due to its weight, has some tendency to vibrate, which impairs the accuracy to which the blades must be ground. Another objection of mounting the grinder by the overhung method or upon one rail only is that it must be of very heavy and rigid construction and as it must be removed after the blades are ground it often requires the services of two men.

With my improved method of mounting a grinder, as will be presently described, I have overcome the above-mentioned objections by supporting the grinder at a plurality of points, decreasing the weight of the motor connections and adding several more positions to the motor which is advantageous in grinding knives to concaved or straight bevels; also, with a decrease in the weight of the grinder, one man can easily attach or remove the unit, when desired.

The objects of my invention, briefly stated, are to provide an improved support for grinders of woodworking machines which is simple, efficient, durable and of considerably less weight than the grinders heretofore used for this purpose.

These and other objects of the invention will be made to appear in the course of the following description in which reference is

made to the accompanying drawings, wherein—

Fig. 1 is an end elevational view of my invention shown partly in vertical section with fragmentary parts of a surfacing machine shown in connection therewith; and

Fig. 2 is a rear elevation thereof, or a view looking in the direction of arrow A in Fig. 1, parts being omitted.

In describing the nature of my invention I have selected for purposes of illustration a surfacer, and shown only those parts of the machine associated with the invention.

Referring to Fig. 1, the numeral 3 designates fragmentary portions of the main frame of the surfacer, 4—4 the stock feed and supporting rollers which are rotatably mounted in bearings in the upper portion of the frame 3, and 5 the cutter head which is provided with removable cutting blades 6. A pair of uprights 7, formed integral with frame 3, are recessed at 8 to receive the cross rail 9, said rail being rigidly fixed to said uprights by means such as the bolts 10. The ends of rail 9 form bearings to receive the feed screw 11 and one end of said screw is provided with a pin 12 whereby a hand crank (shown by broken lines in Fig. 1) can be used for rotating said screw for reasons presently described. In the present showing, rail 9 is mounted horizontally and crosswise of the machine and located above the plane of rollers 4—4 and cutter head 5, and is provided with dovetailed slideways 13—13 upon which saddle 14 is mounted for sliding movement. The upper slideway 13 of rail 9 (as viewed in Fig. 1) fits into the dovetailed recess 15 of saddle 14 and the lower slideway 13 engages gib 16, the latter being secured to said saddle 14 by screws 17, as clearly illustrated, thus permitting the sliding movement of saddle 14 upon rail 9. Bracket 18 is removably fixed to saddle 14 by bolts 19 and is provided with a split bearing 18a at its ends to receive shaft 20. This shaft 20 is fixed to the arm 23 in any suitable manner as, for example, by set screw 20a and is free to move in the split bearings 18a. Should any wear occur between the shaft and the split bearings, such wear can be compensated for by tightening 100

- the screws 18b, as will be readily apparent in Fig. 1. Shaft 20, therefore, pivotally supports the end 22 of arm 23, as clearly shown in Fig. 1. The other end, or end 24 of said arms 23 is provided with a screw threaded opening 25 to receive the threaded screw 26, the lower end of which screw has an integrally formed knob or ball 27 pivotally fitting within sliding member 28. The lock nut 29 is 5 adapted to retain the adjustment of said screw 26 within end 24 of arm 23. The sliding member 28 is supported upon the top surface of horizontal bar 21, which bar is adjustably held within the frame 3 by set-screws 30 and 31, the set-screw 30 serving to retain the adjustment of said bar 21 and the set-screw 31 serving to adjust the bar vertically, which adjustment is maintained by lock-nut 32.
- 10 Arm 23, as shown in Fig. 1, is provided with an enlargement or boss 33 suitably bored out to receive sleeve 34, which sleeve is adapted to be adjusted vertically within the bore of said boss 33 by the threaded-screw 35 and attached hand wheel 36.
- 15 The swivel connection between the motor 37 and arm 23 will now be described:
- 20 Motor 37 is supplied with two lugs or ears 38-38 suitably bored out to receive the axle shaft 39, as shown in Fig. 1. This shaft 39 is also received by the prongs 40-40 of the bifurcated or forked member 41. Set-screws 42-42 serve to lock the shaft 39 with the prongs 40-40 of member 41 and set-screws 43-43 serve to retain the desired adjustment of the motor 37 upon shaft 39. The bifurcated or forked member 41 is held within the sleeve 34 by the swivel bolt 44. Locking screw 45, threaded into the boss 33 serves to hold the member 41 in adjusted position.

- 25 From the foregoing description, it will be clearly apparent that the motor 37 is rigidly suspended from arm 23 in a manner capable of being adjusted in all directions, which, as above stated, aids materially in positioning the grinding wheel 46 relative to the plates 6 of the cutter head 5.
- 30 While I have shown my improved knife grinder support in use on a surfacing machine, it is not my intention that it be limited to this use. It may be adapted to any machine having cutting blades which are sharpened without removing them from the machine. It will be obvious to those skilled in the art that various changes may be made in my device without departing from the spirit of the invention and I, therefore, do not limit myself to what is shown in the drawings and described in the specification but only as set forth in the appended claim.
- 35 Having thus fully described my said invention, what I claim as new and desire to secure by Letters Patent is:

- 40 A grinder structure of the class described comprising the combination of an arm, a

motor pivotally connected with said arm, a saddle, a rail adapted to slidably support said saddle, means for pivotally connecting one end of said arm with said saddle, means for moving said saddle upon said rail, a second rail spaced apart from said first-mentioned rail, means carried by the free end of said arm to slidably engage and be supported by said second rail and means to adjust said motor relative to said arm, whereby vibration of said motor and arm is reduced to a minimum by the use of said pair of rails for supporting said arm.
